Primary Examiner—M. N. Pandozzi(74) Attorney, Agent, or Firm—Hodgson Russ LLPCLAIM

The ornamental design for beverageware, as shown and described.

DESCRIPTION

FIG. 1 is a perspective view of beverageware showing our new design;

FIG. 2 is a front elevational view thereof, the rear, left hand side and right hand side being identical to the view shown; FIG. 3 is a top plan view; and, FIG. 4 is a bottom plan view.

The broken line showing of a lid in FIG. 1 is for illustrative purposes only and forms no part of the claimed design.
